(57) CLAIM

The ornamental design for a shoe sole, as shown and described.

DESCRIPTION

FIG. 1 is a perspective right side view of a shoe sole showing the new design;

FIG. 2 is a perspective left side view of the shoe sole depicted in FIG. 1;

FIG. 3 is a left side elevational view of the shoe sole depicted in FIG. 1;

FIG. 4 is a right side elevational view of the shoe sole depicted in FIG. 1;

FIG. 5 is a front elevational view of the shoe sole depicted in FIG. 1;

FIG. 6 is a rear elevational view of the shoe sole depicted in FIG. 1;

FIG. 7 is a top plan view of the shoe sole depicted in FIG. 1; and,

FIG. 8 is a bottom plan view of the shoe sole depicted in FIG. 1.

The broken lines showing a shoe upper throughout the views; and the broken lines on the sole of the shoe in FIG. 8 illustrate the portions of the article that form no part of the claim.
